UNITED STATES PATENT OFFICE.

JOHN HOLEK AND DAVID SCHWARTZ, OF MILWAUKEE, WISCONSIN.

EXPRESS-SAFE.

1,083,401.

Specification of Letters Patent.

Patented Jan. 6, 1914.

Application filed September 29, 1913. Serial No. 792,514.

To all whom it may concern:

Be it known that we, JOHN HOLEK and DAVID SCHWARTZ, both citizens of the United States, and residents of Milwaukee, in the 5 county of Milwaukee and State of Wisconsin, have invented certain new and useful Improvements in Express-Safes; and we do hereby declare that the following is a full, clear, and exact description thereof.

10 Our invention consists in what is herein particularly set forth with reference to the accompanying drawings and pointed out in the claims of this specification, its object being to provide economical express safes, 15 each having an interior stationary receptacle guarded by a rotary shell in a stationary casing and organized for automatic opening of doors of the casing and shell, when the car has traveled a distance in miles determined by the person closing the safe, 20 provision being had for imparting motion from an axle of the car to said shell, and for starting and stopping said motion from within said car.

25 A further object of the invention is the inclosing of all the locking mechanism of the safe when the doors of the aforesaid shell and casing are locked in closed position.

30 Figure 1 of the drawings represents a vertical central section of an express safe in accordance with our invention, the same being generally indicated by line 1—1 in Figs. 2, 3 and 5; Fig. 2, a horizontal sectional view generally indicated by line 2—2 in Fig. 1; Figs. 3, 4 and 5, sectional views of details of the safe respectively indicated by lines 3—3, 4—4 and 5—5 in Fig. 1; Fig. 6, a partly sectional elevation of a detail of

35 the safe generally indicated by line 6—6 in Figs. 2 and 8, a door in this illustration being partly broken away; Fig. 7, a sectional view indicated by line 7—7 in Fig. 6; Fig. 8, a partly sectional elevation of a detail of 40 the safe indicated by line 8—8 in Fig. 2, and Figs. 9, 10, 11, 12, detail partly sectional views of the safe indicated by lines 9—9, 10—10, 11—11, 12—12, in Fig. 1.

45 Referring by numerals to the drawings, 50 13 indicates the floor of a railway express car, 14 a cylindrical casing having inner bottom lugs 14' bolted to said floor, and 15 a horizontal partition of the casing outwardly extended to form the bottom of an 55 angular outer chamber extension 16 of said

casing, one wall of this extension being in the form of a swing-door 17 shown in Fig. 2. Bolted or otherwise rigidly secured on the partition 15 central of the casing 14 is a shouldered circular pedestal 18, and similarly secured on the pedestal is an inner cylindrical receptacle 19 having an opening thereof closed by a sliding door 20 for which guides 21 are provided exteriorly of said receptacle. The door is held closed by an 60 interior lock having an exposed key-hole 20' shown in Fig. 1, and said door is the only one of the safe having a key-controlled lock. The annular shoulder of the pedestal is a bearing for anti-friction balls 22 that 65 are supported in a circular plate 23 and opposing a similar plate 24 bolted or otherwise rigidly secured to the bottom of a cylindrical shell 25 having a spur-gear ring 26 similarly secured to its bottom. The 70 gear-ring is in mesh with a spur-pinion 27 on a spindle 28 for which the aforesaid casing and its partition are provided with bearings. A spur-gear wheel 29 fast on said 75 spindle meshes with a spur-pinion 30 fast on another spindle 31 for which bearings are also 80 provided in connection with said casing and partition. The spindle 31 is in line with another spindle 32 for which a bearing is provided in connection with the casing partition 15, and fast on the spindle 32 is a 85 clutch-member 33 in which the spindle 31 is sleeved. Guided on the spindle 31 is a sliding clutch-member 34 having an external annular groove engaged by a spanner 90 35 suspended in rigid connection with a shaft 36 for which suitable bearings are provided. The shaft extends outside of the casing 14, and a lever 37 is fast on the outer end of said shaft, said lever being actuated 95 to shift the sliding clutch-member aforesaid.

Fast on the spindle 32 is a ratchet-wheel 38, and a spring-controlled reciprocative pawl 38' therefor is carried in a forked rocker-arm 39 loose on said spindle. A pitman 40 is pivotally connected at one end with the rocker-arm, and its other end is connected with a ring 40' encircling an eccentric 41 fast on a rotary device 42 that may be an axle of the car or a shaft to which 105 motion from said axle is transmitted. Another ratchet-wheel 43 is fast on the spindle 32, and a spring-controlled detent 44 guided in lugs of a bearing for said spindle engages the latter ratchet-wheel. 110

From the foregoing it will be understood that the cylindrical shell 25 has step-by-step rotary motion when the spindles 31 and 32 are in clutch and the car in motion, the 5 clutch-mechanism being under control of a person within the car through the medium of the lever 37. Said shell has an opening therein and this opening is closed by a sliding door 45 for which guides 46 are provided. Guided in lugs upon the inside of 10 the shell-door 45 is a spring-controlled vertically reciprocated bolt 47 opposed by a spring-controlled sliding latch 48 that plays in a slot of the shell bottom through which 15 it extends. To steady the movement of the latch a stem 48' thereof has sliding fit in a wall of the play-slot for said latch, said slot being in a thickened portion of the shell bottom as clearly shown in Fig. 1. The closing 20 of the shell-door 45 causes a retraction of the bolt 47 to clear one side of the latch 48, and as will hereinafter appear there is automatic retraction of said latch to clear said bolt. The door 45 is provided with a lug 25 45', and fast on the shell 25 is a casing 49 for a spring-controlled sliding stem 50 retracted by said lug when said door is closed. Upon release of the door said stem 50 reacts 30 against said lug to start said door into open position.

The depending end of the latch 48 is in the path of an inner upper lug 51' of a slide bar 51 guided in a lug 52 of the partition 15 of the casing 14, as shown in Figs. 2 and 8, 35 said bar being in spring-controlled connection with said lug, as shown at 53 in Fig. 2, automatic movement of the bar against spring-resistance being effected by means hereinafter specified.

40 An opening in the casing 14 is closed by a sliding door 54 for which guides 55 are provided and said door closes past the closed door 17 of the chamber-extension of said casing. Guided in lugs 56 of the door 55 is 45 a vertical spring-latch 57 having a beveled lower end that automatically shifts from one side to the other of the slide-bar 51 when the door 54 is closed and said bar is provided with a latch-clearing notch 57' shown in 50 Fig. 8. The door 54 is provided with a lug 54', and a spring-controlled sliding stem 58 similar to the one 50 is arranged in the path of the lug, as is also shown in Fig. 8. Upon release of the door there is reaction of the 55 previously retracted stem 58 against said lug 54' to start said door into open position. The casing is also provided with an outer swing-door 59 having a spring-controlled latch 60 engageable with the door 54 through 60 a double right-angle slot 61 therein, as shown in Figs. 6 and 7. When the door 54 is automatically started into open position, the clearance portion of its slot 61 registers with

the latch 60, and the reaction of a previously compressed spring 62 with said door 59 will automatically start the opening thereof. The closing of the door 59 is against a jamb notch of the closed door 17 of the chamber-extension 16 of the casing 14, as shown in Fig. 1.

70 The plate 24 in connection with the shell 25 is provided with a lug 24', and arranged in the path of said lug is a spring-controlled lever 63 carrying a spring-controlled pawl 64 in engagement with a ratchet-wheel 65 fast on a spindle 66 for which bearings are provided on the casing-partition 15, and another ratchet-wheel 67 fast on said spindle is engaged by a detent 68. A bevel-gear pinion 69 fast on the spindle 66 engages a horizontal bevel-gear wheel 70 loose on a post 71 rising from a block 72 that also serves as one of the bearings for said spindle, and a circular crown-flange 70' of said gear-wheel is radially notched at predetermined intervals in 80 proportion to miles of travel on the part of the car based upon the number of revolutions of the aforesaid car-axle to each mile of travel on the part of said car.

85 In spring-controlled sliding engagement 90 with the post 71 is a plate 73 that crosses the crown-flange of the gear-wheel 70 and is provided with a depending lug 73' engageable with any one of the notches of said flange. The plate 73 is provided with an indicating 95 pointer 73'' and a stationary index-dial 74 is arranged to oppose the pointer. A bail 75 in connection with the plate 73 serves as a handle to facilitate lift of the same against resistance of its controlling spring 75', and a 100 wiper-lug 76 depending from the plate, clear of the gear-wheel 70, is designed to operate against and pass an outer upper lug 51'' of the slide-bar 51, whereby said bar is operated, against resistance of its controlling 105 spring, to effect an automatic release and partial opening of the shell and casing doors. Carried in connection with the slide-bar is an electric contact 77 that closes on a stationary electric contact 78, the two contacts being put in circuit with an electric signal by which to indicate the unlocking of the then 110 registering shell and casing doors, so that a person in the car may shift the clutch-member 34 out of working position and thus stop 115 rotary movement of the shell 24, as otherwise said shell would in time cut off access to the receptacle 19 through the doorway of the outer casing.

Prior to closing the safe, the operator sets 120 the pointer 73'' to a mark on the dial 74 corresponding to the number of miles the car is to travel before automatic unlocking of the casing and shell doors will take place, the distance being approximate to that between two stations of the railway for said 125

car, after which said doors as well as the casing-chamber door are closed and automatically locked coincidental to the closing. The locking mechanism being wholly within the safe it is non-accessible to the express messenger or any one else in the aforesaid car. When the car is put in motion, the sliding clutch-member is manually shifted to start the rotation of the shell 25. At each 10 revolution of the shell the lever 63 is actuated by the plate-lug 24' of said shell to transmit motion to the spindle 66, whereby step-by-step motion is imparted to the gear-wheel 70 until the wiper 76 of the indicator 15 plate 73 with said wheel is caused to actuate the slide-bar 51 as aforesaid and thus effect a release of the casing and shell doors. The crown-flange 70' of the gear-wheel 70 is herein shown notched at intervals in proportion 20 to ten miles of car travel, but the sub-dividing of said crown-flange for the engagement of the lug 73' of the indicator-plate may be indefinitely varied without departure 25 from our invention as herein claimed, and the slide-bar actuating wiper 76 of said indicator-plate is always diametrically opposite said lug that then engages a sub-dividing notch of the aforesaid flange.

30 As shown in Fig. 1, the indicator plate 73 is adjusted to have its wiper 76 in register with the mark on the dial 74 indicating sixty or one half of a total amount of travel for which it is possible to adjust said indicator. Hence upon the completion of one-half of one revolution of the gear-wheel 70, said wiper will operate upon the slide-bar 51 to effect an opening of all of the safe doors other than the inner receptacle for 35 which some authorized person will be provided with a key.

40 The upper head of the receptacle 19 is provided with a central upper stud 19' that extends through the upper heads of the shell 45 25 and the casing 14 flush with the latter, said shell being loose on said stud.

We claim:

1. The combination of an express safe comprising an inner stationary receptacle 50 provided with a door and independent locking means for the same, a stationary outer casing, and an interposed rotary shell; means for driving the shell from an axle of a railway car containing the safe, lock- 55 mechanism for doors of the shell and casing, lock-release mechanism, means for automatic operation of the lock release mechanism, and means by which to regulate the occurrence of said operation with respect to a 60 variable predetermined number of miles traveled by said car.

2. The combination in an express safe of an inner stationary receptacle provided with a door and independent locking means

for the same, a stationary outer casing and 65 an interposed rotary shell; means for driving the shell from an axle of a railway car containing the safe, means for starting and stopping the drive of the shell under control from outside of the safe, lock-mechanism for doors of the shell and casing, lock-release mechanism, means for automatic operation of the lock-release mechanism, and means by which to regulate the occurrence of said operation with respect to a variable 70 75 predetermined number of miles traveled by said car.

3. The combination of an express safe comprising an inner stationary receptacle provided with a door and independent locking means for the same, a stationary outer casing, and an interposed rotary shell; means for driving the shell from an axle of a railway car containing the safe, lock-mechanism for doors of the shell and casing, lock-release mechanism, means for automatic operation of the lock-release mechanism, and means by which to regulate the occurrence of said operation with respect to a variable 80 85 predetermined number of miles traveled by said car, and means for automatic partial opening of the unlocked doors.

4. The combination of an express safe comprising an inner stationary receptacle provided with a door and independent locking means for the same, a stationary outer casing, and an interposed shell adapted for rotation; a spindle within the confines of the casing and in clutch-controlled gear connection with the shell also within the confines of the casing, means for operating the clutch from without said casing, means for transmitting motion to the spindle from an axle of a railway car containing the safe, lock-mechanism for doors of the shell and 90 casing, lock-release mechanism, means for automatic operation of the lock-release mechanism, and means by which to regulate the occurrence of said operation with respect to a variable 95 100 predetermined number of miles traveled by said car.

5. The combination of an express safe comprising an inner stationary receptacle provided with a door and independent locking means for the same, a stationary outer casing, and an interposed rotary shell, means for driving the shell from an axle of a railway car containing the safe, a lock-mechanism for doors of the shell and casing, lock-release mechanism comprising a spring-controlled slide-bar, a wheel within the confines of the casing and provided with a crown-flange radially notched at intervals thereof in proportion to miles of travel on the part of said car, an inclosed stationary 115 index dial, a pivotally adjustable indicator-plate crossing the dial and provided with a lug engageable with any one of the notches 120 125

of the wheel-flange, a wiper with the plate by which to actuate the slide-bar against spring-resistance, and means by which intermittent motion is imparted to said wheel from said shell.

In testimony that we claim the foregoing we have hereunto set our hands at Milwaukee in the county of Milwaukee and State

of Wisconsin in the presence of two witnesses.

JOHN HOLEK,
DAVID SCHWARTZ.
